UNITED STATES PATENT OFFICE.

GEORGE P. PETERSON, CHARLES E. PETERSON, AND ABNER A. PETERSON, OF ESPANOLA,
WASHINGTON.

ADJUSTABLE HAMES.

No. 921,561.

Specification of Letters Patent.

Patented May 11, 1909.

Application filed April 20, 1903. Serial No. 428,195.

To all whom it may concern:

Be it known that we, GEORGE P. PETERSON, CHARLES E. PETERSON, and ABNER A. PETERSON, citizens of the United States, residing at Espanola, in the county of Spokane, State of Washington, have invented certain new and useful Improvements in Adjustable Hames; and we do hereby declare the following to be a full, clear, and exact description of the invention, such as will enable others skilled in the art to which it appertains to make and use the same.

This invention has relation to hames for horse-collars of the kind that are provided with devices that adapt them to fit collars of different sizes without unbuckling the top hame-strap, and that are contrived so that the point of attaching the traces or 20 tug-straps can be adjusted up or down to suit the shape and size of the shoulders of the particular horse upon which the collar is placed.

It is the object of the invention to provide improvements that will simplify the construction and render it more ready and certain of operation.

The invention consists of the particular construction and relationship of parts herein shown, described and claimed.

Of the drawings forming a part of this specification: Figure 1 is a side elevation of the hame supposed to be suited for use on the right shoulder in the crease between the roll and body of the collar, as usual. Fig. 2 is a rear face view of the steel slide-plate forming the prime means by which the traces or tug is adjusted and maintained in position on the elongated hame-tug staple. Fig. 3 is a similar view of the adjustable plate which controls the position of the strap connecting the upper ends of the hames to suit them to different sizes of collars. Fig. 4 is a transverse section of Fig. 2, taken in the plane 4—4. Fig. 5 is a longitudinal sectional view of the hame-tug staple the adjusting plate and parts of the hame with which the staple and plate are connected.

Similar characters of reference designate corresponding parts.

In the drawings, 1 designates the hame proper which may consist of a wooden body 2, faced on the side of the direction of the pull with steel plate 3 with which the elongated tug-staple 4 is connected.

5 designates a steel plate adapted to slide longitudinally on the hame-plate 3, and provided with a slot 5' through which the upper leg 6 of the tug staple extends. The lower end portion of the plate 5 is outwardly turned, as at 7, and notched at 8. Above the out-turned end 7 of the plate 5 is a similarly notched guide-plate 7' in spaced relationship to the out-turned end 7, and connected at its inner end in any suitable manner with the plate 4. The notches in the guide-plates or ears 7—7' are formed to receive loosely therein the body or main portion of the tug-staple 5.

Above the slot 5' in the plate 5, the latter is provided with holes 9, through any one of which the outer end of a spring-pressed pin, 10, is adapted to project to hold the plate 5 in any position to which it may be adjusted vertically. The pin 10 extends through a hole in the hame-plate 3, and has a spring 11, back of the same, in the wooden part of the hame to keep the said pin pressed normally outward. The inner end of the pin 10 is provided with a laterally-projecting trigger 12, for engagement by the thumb-nail or otherwise to press the pin back against the spring 11 and out of engagement with the holes 9, in the plate 5, to permit of the adjustment of the latter.

The guide-plates 7 and 7' afford means to keep the trace or tug in position on the staple 4, so that by adjusting the plate 5 up or down the vertical point of attaching the tug to the hame may be adjusted accordingly.

13 designates a stud-plate, similar to the plate 5, and adapted to be adjusted on the upper portion of the hames in a similar way, by similar means. In the latter instance 10' designates the spring-pressed pin, 11' the spring back of it, 12' the trigger and 9' the holes in the plate 13 through any one of which the pin is adapted to project. The plate 13 is provided with a slot 5² for the reception of the shank of the terret or reinforcing 14 which is secured to the hame, and said plate 13 is furthermore provided with loops or guides 15 on its outer face for the control in position of the top strap which secures the two hames together, so that by adjusting the plate 13 up or down on the hames, the latter may be adjusted in a well-known way to fit collars of different sizes.

Within the outer face of the wooden body 110

2 is formed a recess 16 and the spring 11 is connected to the underface of the plate 3 and has movement in said recess 16 to permit the disengagement of the pin 10 from 5 the opening 9 with which it has been previously engaged and to effect this movement of the said spring 11 the trigger 12 projects through a curved opening 17 in communication with the recess 16 so that said trigger 10 can be actuated by the finger of a hand of an operator. The trigger 12' also projects through a curved slot 17' in communication with a recess corresponding to the recess 16 and this trigger is adapted to be actuated 15 for disengaging the pin 10' from any one of the openings 9 to permit the vertical adjustment of the plate 13 when found desirable.

It is recognized that parts of the invention may be changed in form and be composed of 20 different material from that described, without departing from the nature or general spirit of the improvements.

What is claimed is—

1. A device for adjusting an attachment to 25 hames comprising a plate adapted to be adjusted vertically on the face of the hames and containing a plurality of openings, locking means engaging the openings to maintain the plate in adjusted position, and a tug member connected with the hames and the 30 plate to guide the latter in its adjusting movement.

2. A device for adjusting the traces vertically on hames, comprising the combination, 35 with the hames of an elongated tug-staple

connected with the latter, a plate adapted to be adjusted vertically on the hames and having spaced guide-projections notched to receive the body of the staple, and having a slot through which one of the legs of the 40 staple extends.

3. A device for adjusting the traces vertically on hames comprising the combination with the hames, of an elongated staple connected with the latter, a plate provided with 45 a plurality of adjusting holes and a slot through which one of the legs of the staple extends, spaced guide projections on the plate notched to receive the body of the staple, and a spring-pressed trigger-provided 50 pin connected with the hames and adapted to engage with and be disengaged from the holes in the plate.

4. A device for adjusting the traces on hames comprising the combination with the 55 hames, of a tug member carried by the latter, a movable plate guided by the tug member and adapted to be adjusted vertically on the hames, and spring actuated means engaging said plate to normally hold the same 60 against movement on the hames.

In testimony whereof, we affix our signatures, in presence of two witnesses.

GEORGE P. PETERSON.
CHARLES E. PETERSON.
ABNER A. PETERSON.
